(57) **CLAIM**

We claim the ornamental design for a ball lacing, as shown and described.

DESCRIPTION

FIG. 1 is a top plan view of a preferred embodiment of a ball lacing of the present design.

FIG. 2 is a left side elevational view of the ball lacing of FIG. 1.

FIG. 3 is a right side elevational view of the ball lacing of FIG. 1; and,

FIG. 4 is a front view of the ball lacing of FIG. 1.

The ornamental design that is claimed is shown in solid lines in the drawings. The broken (dashed) lines shown in FIGS. 1 through 4 are included for the purpose of illustrating environmental elements only and form no part of the claimed design.
